UNITED STATES PATENT OFFICE.

GEORGE H. HARTWELL, OF CAMBRIDGEPORT, MASSACHUSETTS.

EXTENSION-EASEL.

SPECIFICATION forming part of Letters Patent No. 391,608, dated October 23, 1888.

Application filed March 29, 1888. Serial No. 268,834. (No model.)

To all whom it may concern:

Be it known that I, GEORGE H. HARTWELL, a citizen of the United States, residing at Cambridgeport, in the county of Middlesex and State of Massachusetts, have invented a new and useful Improvement in Extension-Easels, of which the following is a specification.

My invention relates to improvements in picture-supports; and it has for its object to provide a simple, cheap, and durable device, which will be extensible to enable it to receive pictures of different sizes; and, furthermore, to provide a support which will engage the upper and lower edges of the picture, and thus hold it from being jarred out of place.

The invention consists in a certain novel construction and arrangement of devices, fully set forth hereinafter, and illustrated in the accompanying drawings, wherein—

20 Figure 1 is a perspective view of the support embodying my improvements. Fig. 2 is a longitudinal vertical section. Fig. 3 is a horizontal sectional view of the same.

Referring by letter to the drawings, A represents the frame of the support, which consists of the divergent side rods, B B, which are formed from a single piece of wire and are connected at their upper ends by the loop F. The lower ends of the side rods, B, are provided 30 with hooks C C to bear on the surface which supports the device, and a channeled or grooved rest, D, is attached at its ends to the side rods near their lower ends. A central half-round rod, E, is arranged between the side rods, B, and is attached at its lower end to the center of the channeled or grooved rest and at its upper end to the loop F, which connects the side rods.

A stationary sleeve, G, is attached to the 40 rod E, near its upper end, and the said sleeve is provided with the rearwardly-extending parallel ears H H, between which the upper end of the swinging leg I is mounted. The swinging leg is also provided at its lower end 45 with a hook, K.

A sliding half-round rod, L, is mounted in the sleeve G and is provided at its lower end

with the sleeve M, which slides on the rod E. A notch or depression, N, is formed in the front side of the loop F at its center, whereby 50 the sliding rod is let into the frame to bring its outer or front side flush with the face of the frame.

A channeled or grooved clip or clasp, O, is attached to the upper end of the sliding rod, 55 and it will be seen that the same may be raised and lowered at will. The picture is engaged at its lower edge in the grooved or channeled rest D and at its upper edge in the grooved or channeled clip or clasp, whereby it is held 60 firmly in position. It will be observed that the weight of the sliding clip and rod will normally hold the former in engagement with the upper edge of the picture.

The half-round central rod and the half-round sliding rod together form a round rod, 65 which corresponds in appearance with the other parts of the support.

Having thus described my invention, I claim—

1. In a picture-support, the combination of the frame having the rest D, the central half-round rod, E, provided with a stationary sleeve, G, the sliding half-round rod L, mounted in the sleeve G, and having a sleeve, M, embracing the rod E, and the clip or clasp on the upper end of the sliding rod, substantially as specified.

2. In a picture-support, the combination, with the frame A, having the divergent side rods, B, and the rest D, attached thereto, of the central rod, E, the stationary sleeve G on the central rod and having the parallel ears H, the swinging leg pivoted between the said ears, and the sliding rod mounted in the sleeve G and having a clip or clasp on its upper end, substantially as specified.

In testimony that I claim the foregoing as my own I have hereto affixed my signature in presence of two witnesses.

GEORGE H. HARTWELL.

Witnesses:

AMY L. HARTWELL,
FANNY C. HARTWELL.
